UNITED STATES PATENT OFFICE.

JULIUS DUSOEVOIR, OF OAKLAND, AND JAMES R. WELCH, OF SAN JOSE, CALIFORNIA.

ENGINE.

1,329,514.

Specification of Letters Patent.

Patented Feb. 3, 1920.

Application filed September 6, 1918. Serial No. 252,876.

To all whom it may concern:

Be it known that we, JULIUS DUSOEVOIR, a subject of the King of Belgium, residing at Oakland, in the county of Alameda, and 5 State of California, and JAMES R. WELCH, a citizen of the United States, and resident of San Jose, in the county of Santa Clara and State of California, have invented certain new and useful Improvements in Engines, of which the following is a specification.

Our invention relates particularly to internal combustion engines, and more particularly to a double opposed reciprocating engine of which the chief characteristics are fixed and alined pistons provided with the necessary valves and ignition equipment, and reciprocating cylinders operating in conjunction therewith and operatively connected to a crank-shaft.

The objects of our invention are to provide an engine of the character indicated that will be perfectly balanced, that is non-vibrating, that may be cheaply manufactured, 25 that is light, simple and practical and yet capable of generating great power, that is easily accessible in all parts, easily cooled and easily assembled and taken apart, simplicity of construction being one of its chief 30 characteristics.

With these objects in view our invention consists in the novel and useful provision, formation, construction, combination and relative arrangement and association of 35 parts, members and features as hereinafter described, shown in the drawings and finally pointed out in the claims.

In the drawings:—

Figure 1 is a side elevation of one embodiment of our improved engine.

Fig. 2 is an end elevation of the engine shown in Fig. 1.

Fig. 3 is a sectional view on line 3—3 of Fig. 1.

Fig. 4 is a sectional view on line 4—4 of Fig. 1.

Fig. 5 is a sectional view on line 5—5 of Fig. 3.

Fig. 6 is a diagrammatical illustration of 50 one position of the reciprocating cylinders.

Fig. 7 is a diagram illustrating our improved engine mounted to rotate on a fixed axis.

Similar characters of reference indicate 55 similar parts throughout the several views.

Referring now more particularly to the

drawings, the numerals 1, 2, 3 and 4 indicate four heads or stationary pistons provided with flanges 1^a, 2^a and 3^a respectively, by means of which the said pistons are fixed in 60 spaced and alined relation to each other through the medium of tie-rods 5, 5^a, 5^b and 5^c and their corresponding nuts 6, 6^a, 6^b and 6^c respectively. The two end stationary pistons 1 and 4 are directed toward each other, 65 and are in the form of hollow cylinders closed at one end as at 7 and 8 and having portions of their side walls removed as at 9 and 10 to render the interiors thereof readily accessible. An exhaust valve is positioned in each piston as at 11 and 12, also an inlet valve as at 13 and 14, and ignition devices as at 15 and 16, respectively.

The two pistons 2 and 3 are alined with pistons 1 and 4 and positioned midway there- 75 between, stationary piston 2 facing stationary piston 1 and stationary piston 3 facing stationary piston 4. These pistons 2 and 3 are equipped with exhaust valves 17 and 18, inlet valves 19 and 20, and ignition devices 80 21 and 22 in a manner similar to pistons 1 and 4 above described.

Mounted to reciprocate upon stationary pistons 1 and 2 is a hollow cylinder 23 provided with a central partition 24 thereby 85 forming two explosion chambers 25 and 26 and providing a bearing 27 for wrist-pin 28. Likewise mounted to reciprocate upon heads 3 and 4 is a hollow cylinder 29 identical in form, shape and size with that above de- 90 scribed and having a central partition 30 thereby forming two explosion chambers 31 and 32 and providing a bearing 33 for wrist-pin 34.

In bearings 35 formed at the juncture of 95 stationary pistons 2 and 3 is mounted a crank-shaft 36 connected to wrist-pin 28 by connecting-rods 37 and to wrist-pin 34 by connecting-rods 38.

The preferred method of operating our 100 improved engine is to successively explode combustible mixtures in the several chambers, an example of its operation being as follows. Suppose the several parts be positioned as shown in Fig. 3 and the charge in 105 chamber 26 exploded. Then the cylinders 23 and 29 will be forced simultaneously outwardly to the positions indicated in Fig. 6, chamber 25 exhausting, chamber 31 being filled with a fresh charge, and the charge 110 previously drawn into chamber 32 being compressed. Upon the ignition and explo-

sion of the compressed charge in chamber 32 the cylinders 23 and 29 are forced back into the first position with chamber 26 exhausting, chamber 25 being filled with a 5 fresh charge and the charge in chamber 31 being compressed. The next two explosions would occur in chambers 31 and 25 respectively with the other chambers being exhausted, refilled or compressing a charge as 10 the case may be. This operation as described is illustrative only as any other desired sequence of explosions may be used without departing from the spirit of the invention.

15 Various methods may be used for operating the inlet and exhaust valves. We have illustrated as one method of operating a valve as 12, a shaft 39 geared to crank-shaft 36 at 40 and 41. Upon cam shaft 39 is placed a cam 42 which operates a bell-crank 43 pivoted at 44, the end of the shorter arm 45 of said bell-crank operating in contact with the said valve mechanism 12. Valves 11, 13 and 14 may be operated in a 20 similar manner by cams 46, 47 and 48 operating bell-cranks 49, 50 and 51 respectively.

Valves 17, 18, 19 and 20 may be operated in any suitable manner as by bell-cranks 52, 53, 54 and 55 pivoted at 56 and 57 and 25 operated independently of each other by said cams 42, 46, 47 and 48 so that each of said valves may be operated in conjunction with the proper valve mechanism of one of the end pistons.

30 Various methods of ignition may also be employed. We have shown herein a magneto at 58 to operate the several ignition devices 15, 16, 21 and 22.

In Fig. 7 the engine is indicated as balanced upon a fixed shaft mounted on base 40 59 so that the operation of the engine as hereinbefore described will cause the engine to rotate about the shaft 36.

45 From the foregoing description in connection with the accompanying drawings, it will be seen that we have provided a construction in which the fixed pistons are rigidly mounted in axial alinement, serving both as abutments to form part of the several combustion chambers and as guides and supports for the reciprocating cylinders, thereby greatly simplifying the engine and obtaining increased efficiency per given pound of weight. The construction shown 50 is such that all parts of the engine may be readily reached without taking it apart, but it may be taken apart quickly by simply uncoupling the tie-rods and connecting-rods and disengaging the cylinders from the 55 pistons upon which they operate.

60 It is particularly pointed out that the engine is perfectly balanced because the several fixed pistons and the reciprocating cylinders must be and are in perfect axial alinement and are made uniform in size and 65

weight. Each movement of any portion of the engine in one direction is balanced by a similar movement of a corresponding part of the engine in the opposite direction, even the weights and movements of the connecting-rods being equally balanced. The doubled cylinders 23 and 29 are uniform in shape, size and weight and move simultaneously exactly an equal distance in opposite directions. The perfect balancing of 70 both the movable and immovable parts equalizes the strains upon the engine and consequently reduces the loss of energy through friction. The perfect balancing of 75 the engine eliminates vibration and the energy that would otherwise be dissipated through vibration is conserved and added to the working energy and the efficiency of the engine thereby increased.

80 Increased efficiency is also secured by the use of comparatively long connecting-rods whereby their angle with the throw of the crank is materially reduced, attention also being called to the increased efficiency obtained by having the crank exactly midway between the reciprocating cylinders and the said connecting-rods attached to said cylinders exactly midway their length so that the work of each double cylinder is equally divided between its two halves. It is further pointed out that the construction of the 90 various parts is such that free circulation of air is obtained not only around the cylinders themselves but also through the interior of the fixed pistons, this feature as 95 consisting materially in heat radiation and consequent efficiency of the engine.

100 It is understood, of course, that we do not wish to confine ourselves to the specific form and construction above described, as various changes may be made to meet the requirements of practical application and exigencies of manufacture, but within the scope of the appended claims. Also the method of operation and the motive power 105 used may be changed as deemed necessary without departing from the spirit of the invention, that method of operation being described which is considered at present to be the most desirable to secure the best results.

110 We claim:

1. An engine comprising a double-headed, hollow, cylindrical piston having a crank-shaft passing transversely through the center thereof and having an exhaust and inlet valve and ignition means operatively positioned in each head thereof, an opposing piston fixedly positioned in axial alinement with and in spaced relation to each head of 115 said double-headed piston and having inlet and exhaust valves and ignition means operatively positioned therein, a double cylinder 120 operatively mounted to reciprocate on each pair of opposed pistons, and connecting rods 125 130

operatively attached to said double cylinders and to the said crank shaft.

2. An engine comprising a double-headed, hollow, cylindrical piston having a crank-shaft passing transversely through the center thereof, having an exhaust and inlet valve and ignition means operatively positioned in each head thereof, and provided with openings to render the interior thereof accessible, an opposing piston fixedly positioned in axial alinement with and in spaced relation to each head of said double-headed piston and having an inlet and an exhaust valve and ignition means operatively positioned therein, crank-shaft operated bell-cranks operatively mounted to engage said valves at predetermined periods, a double cylinder operatively mounted to reciprocate on each pair of opposed pistons, and connecting rods operatively attached to said double-cylinders and to the said crank shaft.
3. An engine comprising a double-headed, hollow, cylindrical piston having a crank-shaft passing transversely through the center thereof, flanges extending outwardly from the central portion thereof, an inlet and an exhaust valve and ignition means operatively positioned in each head thereof, and provided with openings to render the interior thereof accessible, an opposing piston spaced a distance from each head of said double-headed piston and having an inlet and an exhaust valve and ignition means operatively positioned therein, provided with openings to render the interior thereof

accessible and having flanges extending outwardly from the outer ends thereof, rods passing through all of said flanges to secure all of said pistons in fixed axial alinement with each other, a double cylinder operatively mounted to reciprocate on each pair of opposed pistons, and connecting rods operatively attached to said double cylinders and to the said crank-shaft.

4. An engine comprising a pair of opposed pistons, having portions of their sides removed and having their outer ends open and provided with flanges, a pair of oppositely directed pistons positioned intermediate said opposed pistons having portions of their sides removed and joined at their abutting ends and provided with flanges, rods passing through all of said flanges and secured thereto for locking all of said pistons in fixed spaced and axially alined relation to each other, a crank-shaft operatively mounted between the abutting ends of said oppositely directed pistons, a pair of double cylinders, each double cylinder being operatively mounted to reciprocate upon one of said opposed pistons and the adjacent intermediate piston, a pair of connecting-rods operatively connected to each double cylinder intermediate its length and to the said crank-shaft, and means whereby said double cylinders may be caused to reciprocate simultaneously but in opposite directions upon their respective pistons.

JULIUS DUSOEVOIR.
JAMES R. WELCH.
